(57) **CLAIM**

The ornamental design for a drive chain measuring tool, as shown and described.

DESCRIPTION

1. Drive chain measuring tool

1.1 : Front

1.2 : Back

1.3 : Top

1.4 : Bottom

1.5 : Right

1.6 : Left

1.7 : Perspective

The design shows a drive chain measuring tool. The broken line showing of the middle of the drive chain measuring tool is for the purpose of illustrating portions of the drive chain measuring tool that form no part of the claimed design.

1 Claim, 7 Drawing Sheets
